Kerr Page Cooper & Hayward

UNITED STATES PATENT OFFICE.

OSCAR A. ROSS, OF NEW YORK, N. Y.

TELEPHONE INSTRUMENT OR THE LIKE.

1,389,902.

Specification of Letters Patent. Patented Sept. 6, 1921.

Application filed April 26, 1918. Serial No. 230,963.

To all whom it may concern:

Be it known that I, OSCAR A. ROSS, a citizen of the United States of America, residing at 154 W. 57th St., New York city, 5 in the county of New York and State of New York, have invented a new and useful Improvement in Telephone Instruments or the like, of which the following is a specification.

10 My invention belongs particularly to that class of telephone instruments comprising the receiving and transmitting units with co-operating circuit controlling devices commonly called a telephone stand and forms 15 part of the apparatus known as the "subscribers set."

My invention refers more particularly to that type of instrument which is portable within the limits of the connecting cord, or 20 wire which attaches said instrument to the "ringer unit."

Telephone instruments of well known construction and which are now extensively employed, are usually constructed of two parts, 25 one a receiver and the other the portable stand comprising the transmitter, a hook for holding the receiver and co-operating circuit controlling apparatus. In instruments of this type, a cord, or wire is supplied between 30 the ringer unit and said portable stand, also a second cord is connected between said stand and the receiver. This second cord affords considerable nuisance as it becomes tangled and twisted, often breaking, thereby interrupting the circuit to the receiver and placing the instrument out of service. Further it is often in the way as the instrument is to be used and must be pre-arranged before 35 telephonic communication can be carried on. 40 One of the objects of my invention is to entirely eliminate said second cord, or wire by combining the receiver in said telephone stand, at the same time not destroying its feature of portability.

45 Further, when the two piece instrument is employed in places of business where it is necessary to use one hand for recording all, or part of the conversation carried on over such instrument, it is necessary to accommodate 50 date the body in a manner which permits the lips of the person talking to be within

proper distance of the mouth-piece on said instrument. As it is often inconvenient and awkward to thus accommodate the body, conversation is carried on with the lips a considerable distance from the transmitter, in 55 this manner often requiring repetition of conversation causing annoyance and delay. Another object of my invention is to produce a telephonic instrument, which, while portable will compel the user of said instrument to maintain practically the proper distance between his, or her lips and the mouth-piece, or transmitter of said instrument.

Further, when a two piece instrument of 60 many well known types is employed, it is very convenient to "joggle the hook," that is, to rapidly operate the lever controlling the cutting in and out of circuits to said instrument, in this manner calling attention of the 65 station operator in an unnecessary manner. Such practice is destructive to the hearing of switch-board operators and causes delay and annoyance. A further object of my invention therefore is to make such joggling of 70 the hook difficult and inconvenient to do, thereby discouraging such practice.

All the above and other objects are attained in the instrument which, for purposes of illustration is shown in the accompanying drawings, in which,

Figure 1, is a transverse section through the preferred form of my instrument taken on line C—C, of Fig. 4, and,

Fig. 2, is a plan view looking in the direction of line B—B, of Fig. 1, and

Fig. 3, is a cross sectional view on line A—A, of Fig. 1, and,

Fig. 4, is a part plan, part sectional view of the base of the instrument taken on line D—D, of Fig. 1, and,

Fig. 5, is a reduced side elevation of my preferred form of instrument, and,

Fig. 6 is a reduced size front elevation of the instrument as shown in Fig. 5, and,

Fig. 7, is a reduced size top elevation of the instrument as shown in Figs. 5 and 6, and,

Fig. 8, is a diagrammatic arrangement of circuits and apparatus of a subscriber's set, illustrating the adaptation of my improved 100 instrument therewith.

None of the several units employed in

making up my improved instrument need be, of any special or unusual construction, but for more ready understanding of my invention I have illustrated the transmitter 5 and receiver as standard appliances employed by the American Bell Telephone Company.

The description of my improved form involving the heretofore named transmitter 10 and receiver, is as follows:

Referring to Fig. 1, 1, is the receiver unit, or top piece of the instrument. 2, is the base containing transmitter unit 74, of which diaphragm 3, is a part and is adapted 15 to receive the sound waves through holes 4. The distance between receiver 1, and holes 4, is preferably such, that when said receiver is held against the ear and holes 4, opposite the mouth of the person talking, 20 the best results for telephonic communications are obtained. Connecting the base 2, and top piece 1, is a tube 5, which is secured to top piece 1, by screws as 6, and is pressed into and otherwise secured into receptacle 25 7. Said receptacle is rigidly secured to plate 60, and sheet metal housing 8, of base 2. Secured to tube 5, are collars 9 and 10, which act as guides for movable tube 11. 30 12 and 13, are felt collars cemented to molded insulation 14 and receptacle 7, and act to prevent dust and dirt from interfering with the proper movement of tube 11. Secured to tube 11, and passing through the slotted holes 16, in tube 5, are screws 17, and 18. 35 Screw 17, enters internally into screw 18, forming a double headed pin. Resting against shoulders of screws 17 and 18, are the upper projections of yoke 19, said yoke being secured to and forming part of yoke 40 20, having mounted thereon insulated sleeve 21, supported by pin 22, riveted into said yoke 20. Operating tube 11, is shown in its out of service position, the lower end thereof resting against stop 25, in receptacle 7. 45 Assume now that it is required to place the instrument in service for communication. The party using the instrument places his left hand around tube 11, and lifts the instrument from its place of rest. By this 50 procedure, as the instrument is raised, the weight of the various parts causes tube 11, to move upward until its upper end impinges against stop 26. By this movement yokes 19 and 20, with insulating sleeve 21, are carried upward permitting contact springs 27 and 28, to contact with plate 29, thereby establishing the necessary circuits to the receiver and transmitter of the instrument as 55 illustrated in Fig. 8. The functions performed by raising of tube 11, are analogous to those performed as the receiver is removed from the hook of the telephone as furnished by the American Bell Telephone Company.

If, for any reason it should be required to leave the instrument in telephonic communication for any length of time, as for example, if the party using the telephone were compelled to leave the room to call another party, the push button 66, is depressed 70 against the action of spring 68, and tube 11, is permitted to lower into groove 69, of push button 66. This position of tube 11, while permitting the insulated sleeve 21 to approximate springs 27 and 28, does not cause 75 said sleeve to force said springs away from plate 29 and therefore the instrument remains in service. Sleeve 67, is screwed onto the inner extension of push button 66, and serves to limit the outward movement thereof. When the instrument is again raised by tube 11, and as said tube leaves the groove 69, in push button 66, said button will move outward under pressure of spring 68 to the 80 normal position as shown, this action being 85 automatically performed.

Contact spring 27, is riveted to terminal piece 61, and spring 28, to piece 62. Said terminal piece is connected to terminal 36, of transmitter unit 74, by cable 63. The 90 contact springs 27 and 28 and terminal pieces 61 and 62 therefore are clamped between insulation blocks 30 and 76, and terminal plate 29, between blocks 76 and 77. Metal plate 78 under pressure of nuts 79— 95 79, on studs as 80, serve to hold all said parts in place. Studs as 80, are secured to housing 8, preferably by welding.

Plate 60 has bent up lug 59, into a hole of which is threaded the anchor cord 58, of 100 conductor cable 49, said anchor cord being wrapped around and tied to said lug 59. This serves to prevent any chafing of the cable and strains of the various branches running to their respective terminals as 105 shown.

Bottom cover plate 44, on its lower side is covered with felt sheeting 45 retained in place by band 48, said band also enters into and serves to align the entire cover unit 73, 110 with base housing 8, being secured thereto by nuts 47 screwed onto studs 46—46, secured to said housing.

In tube 5, are guide tubes as 50, in which pass the conductors as 51, leading to terminal posts 52—52, forming terminals for receiver unit coils 42—42, mounted on soft iron pole pieces 39 and 40. Said pole pieces are embedded in molded insulation piece 14 and have angular extensions 71 and 72, 120 which seat on the polar extensions of permanent magnet 37. Such seating is accomplished by the action of spring 65, one end of which forces magnet 37 upward, the other seating on pin 38, secured to tube 5. 125

Receiver unit 1, has opening 82, covered by plate, or cover 54, secured by screws 55 and 56, screw 56 entering sleeve 53 em-

bedded in molded piece 14. Ear piece 43, screwed to molded piece 14, serves to accommodate the ear to receive messages issuing from diaphragm 41, and also serves to hold said diaphragm in place.

Transmitter unit 74, is composed of diaphragm 3, the outer edge of which is supported by band 32. Its center is secured to one terminus of the microphone, the other 10 end of which is secured to terminal post 36. Said terminal post is mounted on but insulated from, by insulation 35, yoke 34, secured to plates 70—70, by screws 75. Said plates 70, are secured to housing 8, preferably by welding.

Cable, or cord 49, forms the electrical connection between the instrument and the ringer set as illustrated by numeral 83, in Fig. 8. Said figure is a typical circuit involved in a subscriber's set and which will be well understood by those versed in the art. 1, is the receiver unit, or top piece and 20 74 the transmitter as shown in Fig. 1. 27, 28 and 29, are likewise the contact members 25 shown in the Figs. 1 and 4, and it will be sufficient to relate that when said contact members are electrically connected with each other the receiver 1 and transmitter 74, are placed in circuit to deliver and receive 30 speech in a manner well known to those versed in the art. 84, is the usual condenser employed and 87 the induction coil. 85 and 86 are line wires communicating with the co-operating telephone exchange.

35 It will be evident to those skilled in the art that various modifications may be made without departing from the spirit of my invention. While I have herein shown and particularly described one embodiment of 40 my invention, I do not wish to be limited to the precise construction as illustrated, as changes may be made without departing from the spirit of my invention.

This application is a continuation in part 45 of my application Serial Number 144,470 filed January 25, 1917.

What I claim is:—

1. In an instrument of the kind described, the combination with a base for supporting 50 the instrument containing a transmitter, a top piece containing a receiver, a body portion connecting these two parts, means for holding said instrument when in service interposed between said base and top piece, 55 said holding means controlling the circuits of said instrument by relative movement of said holding means and base, and means to lock said holding means in moved position caused by holding the instrument.

60 2. In a portable telephone instrument, a base normally adapted to support said instrument, a transmitter unit contained within said base, a receiver unit, a body portion connecting said base and receiver unit,

means for holding said instrument when in 65 service, said means by relative movement with said body portion controlling the circuits of said instrument and means to lock said holding means in moved position caused by holding the instrument, said means 70 adapted to automatically release when said holding means is actuated in raising said instrument.

3. In a portable telephone instrument, a base normally adapted to support said instrument, a transmitter unit contained within said base, a top piece comprising a receiver unit, a body portion connecting said base and top piece, in combination with means interposed between said base and top 75 piece for controlling the circuits of said instrument and for lifting said instrument and means for locking said controlling means in operative position said means adapted to automatically release upon the 80 succeeding operation of said controlling means.

4. In a telephone instrument of the kind described, a base normally adapted to support said instrument, a transmitter unit 90 forming a component part of said base, a receiver unit, a body portion connecting said base and receiver unit, movable means on said body portion for manually supporting said instrument when in telephonic 95 service, said movable means adapted to cut said instrument in or out of service dependent upon a relative movement with said body portion and means for locking said movable means in the in service position 100 said means adapted to automatically release when said movable means are actuated in raising said instrument bodily.

5. In an instrument of the kind described, the combination with a base for supporting 105 the instrument containing a transmitter, a top piece containing a receiver, a body portion rigidly connecting these two parts, means for holding said instrument when in service interposed between said base and 110 top piece, said holding means controlling the circuits of said instrument by relative movement of said holding means and said base substantially as described.

6. In a portable telephone instrument, a 115 base normally adapted to support said instrument, a transmitter unit contained within said base, a receiver unit, a body portion rigidly connecting said base and receiver unit, means for holding said instrument when in service, said means by relative movement with said body portion controlling the circuits of said instrument.

7. In a portable telephone instrument; a base normally adapted to support said instrument, a transmitter unit contained within said base, a top piece comprising a receiver unit, a body portion connecting

said base and top piece, in combination with means interposed between said base and top piece for controlling the circuits of said instrument and for lifting said instrument substantially as described.

8. In a telephone instrument of the kind described, a base normally adapted to support said instrument, a transmitter unit forming a component part of said base, a receiver unit, a body portion rigidly connecting said base and receiver unit, movable

means on said body portion for manually supporting said instrument when in telephonic service, said movable means adapted to cut said instrument in or out of service 15 dependent upon a relative movement with said body portion substantially as described.

In testimony whereof, OSCAR A. ROSS has signed his name to this specification this 20th day of April, 1918.

OSCAR A. ROSS.
